CLAIM

The ornamental design for a recumbent tricycle as shown and described.

DESCRIPTION

FIG. 1 is a front elevation view of a recumbent tricycle showing my new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof; and,

FIG. 7 is a top, front and right side perspective view thereof. The broken lines are illustrative of stitching forming no part of the claimed design.
